CLAIM

The ornamental design for a spray head for shower as shown and described.

DESCRIPTION

2.1 : Perspective

2.2 : Perspective

2.3 : Front

2.4 : Rear

2.5 : Left

2.6 : Right

2.7 : Top

2.8 : Bottom

Fig. **2.1** is a front, left and top side perspective view of a spray head for shower showing our new design; Fig. **2.2** is a rear, right and bottom side perspective view thereof; Fig. **2.3** is a front elevation view thereof; Fig. **2.4** is a rear elevation view thereof; Fig. **2.5** is a left side elevation view thereof; Fig. **2.6** is a right side elevation view thereof; Fig. **2.7** is a top plan view thereof; and Fig. **2.8** is a bottom plan view thereof; The broken lines shown in the drawings represent portions of the spray head for shower that form no part of the claimed design.
